REGENERATOR FOR THE RECOVERY OF
THE COLD CONTENT OF GASES

Herman F. Buschow, North Arlington, and Percival C. Keith, Peapack, N. J., assignors to Hydrocarbon Research, Inc., New York, N. Y., a corporation of New Jersey

Application November 1, 1947, Serial No. 783,498

17 Claims. (Cl. 257—227)

1

The present invention relates to an improved regenerator for recovering the cold content of the outgoing oxygen and nitrogen products of rectification, which may be at a temperature of about -280° F., in the production of oxygen by the liquefaction and rectification of air. More particularly it relates to the construction and design of the regenerators including the cold exchange surface areas therein so as to provide for high cold transfer efficiency between the oxygen and nitrogen products of rectification on the one hand and the air on the other, and for efficient purging of the regenerators upon each reversal of flow therethrough to effect substantially complete removal from the regenerators of condensibles deposited from the air stream, thereby permitting continuous operation.

Cold regenerators are well known in which the relatively warm incoming air and the relatively cold outgoing oxygen and nitrogen products of rectification are passed with periodically reversed operation, so that streams of warm air are flowed through the same packing-filled spaces as the cold oxygen and nitrogen traversed during the preceding step of the process. In the operation of such regenerators the high boiling impurities deposited in the packing-filled spaces during the passage of the air therethrough are removed by sublimation during the subsequent flow therethrough of the products of rectification. In order to provide relatively high cold transfer efficiency such regenerators have involved the use of so-called "pancakes" of heat transfer material formed by winding successive convolutions of corrugated metal on a core to produce disks consisting of successive convolutions of corrugated metal, a multiplicity of which disks are inserted in the regenerator shell one on top of the other to provide the packing for the regenerator. The production of such packing is arduous and time consuming and greatly increases the cost of the regenerator.

Among the objects of this invention is to provide a cold regenerator having an exceptionally high area of cold exchanger surface per unit of volume, which can more readily be fabricated and assembled than heretofore known regenerators and in the operation of which unusually low pressure drop takes place in the fluid flowing therethrough.

Another object is to provide a regenerator packing member, which can readily be produced by a simple stamping operation, and which can readily be assembled within the regenerator

2

housing to produce longitudinally extending channels for turbulent flow of gaseous media therethrough.

Still another object is to provide such regenerator which is more efficient in operation in that the cold transfer rate is considerably greater than in prior known regenerators.

Other objects and advantages of this invention will be apparent from the following detailed description thereof.

In the accompanying drawings forming a part of this specification and showing for purposes of exemplification preferred forms of this invention with out limiting the claimed invention to such illustrative instances:

Figure 1 is a plan view of a preferred form of regenerator packing member on an enlarged scale and illustrates a preferred embodiment of this invention;

20 Figure 2 is a composite section taken in planes passing through lines 2—2 on Figure 1;

Figure 3 is a vertical section taken in a plane passing through line 3—3 on Figure 1;

25 Figure 4 is a perspective view of a regenerator packing unit showing the members of Figure 1 arranged in a stack on a supporting tube;

Figure 5 is a plan view of a modified form of a regenerator packing member on a smaller scale than the scale of Figure 1;

30 Figure 6 is a view partly in elevation and partly in section of a regenerator embodying this invention;

Figure 7 is a diagrammatic section through the regenerator of Figure 6 taken in a plane 35 passing substantially midway between the ends of the regenerator packing units, one of which is shown in Figure 4;

Figure 8 is a diagrammatic elevational view of a regenerator assembly, the colder portion of one of the regenerators being broken away to show the interior construction; and

Figure 9 is a diagrammatic view of a regenerator assembly involving two sets of regenerators, each set consisting of two pairs of regenerators one of which pairs is broken away to show the interior construction thereof.

The regenerator packing member of Figures 1 to 3 is a substantially square shaped plate-like member defined by the sides 10, 11, top edge 12 and lower edge 13. It may be made of any relatively thin material of high heat conductivity, preferably aluminum or copper. Edges 12 and 13 are formed with narrow integral flanges 14 and 15. The packing member has a central

supporting opening 16 defined by an integral flange 17.

Two series 18 and 19 of closely spaced passages 20 are formed in the face of the packing member. A narrow portion of the face of the packing member or rib 21 extends in a generally straight line direction from side 10 to the opening 16 and a like rib 22 extends from the other side of opening 16 to side 11. Ribs 21, 22 separate the two series of passages 18 and 19. The sides of each passage 20 of the two series 18 and 19 are defined by a pair of vanes 23. Each of the vanes 23 extends in a plane at an angle, preferably a right angle, to the plane of the face of the packing member and is integrally joined at its ends with the packing member by the volutes or deflected portions 24. Each of the vanes 23 is produced by cutting through the plate-like member along lines of cuts which preferably but not necessarily are parallel and are spaced apart a distance equal to the width of passages 20, plus the thickness of the plate-like member, and deflecting the material between each pair of cuts to the position shown most clearly in Figure 3, so that the material extends in a plane at an angle of from 60° to 90°, preferably 90°, to its original plane, i. e., to the plane of the plate-like member. One-half of the material thus deflected extends above and the other half below its original plane, the flanges 14 and 15 extending beyond the vanes 23, as is clearly evident from Figures 2 and 3.

In the embodiment of the invention shown in Figures 1, 2 and 3 substantially the entire area of the plate, from which the packing member is formed, is deflected to produce the vanes 23, narrow area or rib 26 along the longitudinal median of the plane and the ribs 21, 22 along the transverse median. Along the areas contiguous to the sides 10 and 11 half vanes 25 are formed by deflecting the material between these marginal areas and the cut contiguous thereto of the series of cuts hereinabove mentioned. Thus each quarter of the plate-like member is formed with a group of narrow passages 20 defined by the vanes 23, all of which passages are in heat transfer relationship with the passage defined by the central opening 16 at one end through a path of heat conducting material consisting of the rib 21 or 22 and at the opposite end through a path of heat conducting material consisting of the flange 14 or 15 and the longitudinally extending rib 26. In other words, ribs 21, 22 and 26 serve as heat conducting bridges between all of the passages leading into these ribs, including those most remote from central opening 16, and this opening 16.

While the packing member of Figure 1 is shown as of square shape it may be of any desired polygonal shape which permits ready nesting of stacks of the packing members with little or no space between contiguous stacks. Thus, for example, these packing members may be of other rectangular shape than the square shape shown, or they may be of hexagonal or triangular shape. Figure 5, for example, shows a hexagonal shaped packing member. In this figure a series 27 of closely spaced passages is formed in the upper half of the packing member and another series 28 of closely spaced passages is formed in the lower half. Each passage is produced by deflecting the material between parallel lines of cuts to form vanes defining the side walls of the passage as hereinabove fully described in connection with Figures 1, 2 and 3. In Figure 5, the two series 27 and 28 are separated by a narrow portion or rib 29, which rib extends from

the central supporting opening 16 to opposite corners of the hexagonal member. The two series of passages 27 and 28 are surrounded by a narrow marginal portion 30 of the plate-like member. Spacer flanges corresponding to flanges 14, 15 of Figure 2 are formed on all the marginal edges of the packing member of Figure 5, or, if desired, on only some of these edges, say on two opposite edges only.

In order to provide the large mass of high heat conducting material per unit of regenerator volume and high area of cold exchanger surface per unit of regenerator volume necessary for effectively recovering the cold content of the outgoing products of rectification, it is important the material of high heat conductivity of each of the packing members be relatively thin. Desirably each packing member is dimensioned so that its thickness does not exceed .040 inch, the spacing between contiguous vanes does not exceed .100 inch and the flanges are dimensioned so as to provide a clearance of .003 inch to .020 inch and preferably from .003 inch to .010 inch between the edges of the vanes of contiguous packing members when the flange of one member abuts the face of a contiguous member. Preferred dimensions for an aluminum packing member of the shape shown in Figures 1, 2 and 3 are as follows: thickness .032 inch, depth of flanges 14 and 15—.105 inch, width of each passage 20—.048 inch, depth of vane 23—.08 inch, of which part extends above and part below the original plane of the material from which the vane is produced by deflection of the material as hereinabove described, diameter of central opening 16—.75 inch, width of ribs 21, 22— $\frac{1}{8}$ of an inch.

It will be noted that each of the packing members may easily be fabricated by a simple stamping and cutting operation in which the cuts defining the inner edge of flange 17 and the edges of the vanes 23 are first produced and then the material deflected to form the integral flanges 14, 15 and 17, the half vanes 25, the vanes 23 defining the passages 20 therebetween, and the ribs 21, 22 and 26 providing a bridge of high heat conducting material between all of the passages and the central opening 16.

The packing members hereinabove described are mounted on a supporting tube 31 to form a packing unit such as shown in Figure 4. The supporting tube 31 desirably is a hollow tube of high heat conducting material, for example, aluminum or copper, having relatively thin walls, e. g., about .12 inch thick, and having integral interior fins 32 extending from the inner wall in a radial direction towards the center of the tube to improve the efficiency of the heat exchange between the gaseous medium passing through tube 31 and that flowing through the channels 20 in the packing member. The outside diameter of the tubes is substantially the same as the diameter of the central supporting opening 16 in each of the packing members so that the packing members fit snugly on the tube. The packing members may readily be mounted on the supporting tube 31 by passing the tube through the central opening 16 of a stack of the members suitably grouped to form the desired regenerator unit; preferably the individual packing members are arranged in alternate groups 33, 34. All the packing members in the groups 34 in the embodiment of the invention shown in Figure 4 have the passages 20 therein extending in a generally vertical direction, while all of the packing members

of each of the groups 33 have the passages 20 therein extending in a generally horizontal direction. Such grouping of the packing members of each stack results in a turbulent flow of the gaseous stream through the regenerator and improves the heat transfer efficiency of the regenerator.

The individual packing members desirably have the flange 17 brazed to the supporting tube 31 and thus bonded thereto. Also either the corner portions of flanges 14 and 15, or the entire longitudinal extent of these flanges, may be brazed to the abutting portion of the face of the contiguous member. The ends 35, 36 of the supporting tube 31 of each packing unit extend beyond the stack of packing members mounted thereon for the purpose hereinafter described.

Each of the packing units before assembly with other like units to form the regenerator packing, as shown in Figure 6, has bearing members 37, 38 positioned at the opposite ends of the stack of plate-like packing members. Desirably one or more such bearing members 39 are positioned at an intermediate point of the stack of packing members of each packing unit. These bearing members may be formed, for example, by winding one or more layers of a foil-like material, for example, aluminum foil, about each packing unit. Preferably two layers of aluminum foil 3 inches wide are wound or wrapped about each packing unit to form the bearing members 37, 38, 39. When the packing units are assembled the bearing members of contiguous units are in contact with each other maintaining a small clearance 40 between individual packing units, thereby preventing the packing members of one unit from rubbing against the packing members of another unit, and thus minimizing damage to the packing members of each unit.

Ends 35 of the tubes 31 pass through collars 41, 42 which are welded or otherwise fastened to beams 43 extending transversely through the upper part of shell or housing 44. The ends of beams 43 are suitably fastened to the housing 44, for example, by welding. Two rows 45, 46 of packing units are suspended from the opposite sides of each beam. The packing units of each row are disposed, as hereinabove described, with the bearing members 37, 38, 39 on each of the packing units in abutting relationship. The packing units of each pair of rows 45, 46 are mounted on opposite sides of each beam 43 and have their bearing members 37, 38 and 39 in abutting relationship, as clearly appears from Figure 6. These bearing members on each of the packing units of each row 45 suspended from one beam 43 are disposed in abutting relationship with the bearing members on the packing units of row 46 suspended from an adjacent supporting beam 43. As shown in Figure 7 the packing units of one row 45 may be offset relative to the position of the packing units of the contiguous row 46. The space between the outer packing units and the inner wall of shell 44 is filled with aluminum foil 47, or may otherwise be blocked off to avoid flow through this space. Alternatively, the exterior of shell 44 may be accurately dimensioned so as to fit the contour of the arrangement of individual packing units formed by grouping these packing units in closely spaced relationship with the bearing members in contact, as shown, for example, in Figures 6 and 7. The regenerator should contain not less than 15 or 20 individual packing units, the exact number

depending on the volume of oxygen, nitrogen and air to be handled.

A header 48 is disposed at one end of regenerator housing 44 and a second header 49 positioned at the other end of this housing. Extending across each of these headers and suitably secured thereto as by welding is a series of manifolds 50, there being one such manifold connected with each of the headers 48, 49 for each pair of rows 45, 46 of packing units. Ends 35 of the tubes 31 of each pair of rows of packing units are connected with manifold 50 communicating with header 48 and the opposite ends of these tubes are connected with manifold 50 communicating with header 49. Thus all of the tubes 31 of the packing units are communicably connected at their opposite ends with the headers 48 and 49. A port 51 provided with an expansion joint 52 leads into header 48 and a port 53 provided with an expansion joint 54 leads into header 49.

Housing 44 is formed with a top port 55 and a base port 56. A stand 57 is provided for supporting the regenerator in the upright position shown in Figure 6. If desired, however, the regenerator may be constructed for placing in a horizontal position on a suitable support.

In Figure 8 a regenerator assembly is shown involving two regenerator pairs 58 and 59. Regenerator pair 58 consists of regenerators 60, 61 each structurally substantially the same as the regenerator of Figure 6. Regenerator pair 59 consists of regenerators 62, 63 each structurally substantially the same as the regenerator of Figure 6. Parts of the regenerators 60, 61, 62 and 63, the same as those of the regenerator of Figure 6, are indicated by the same reference characters. Regenerators 60, 61 and 62, 63 have the ports 56, 55 interconnected for flow from one regenerator to another, as shown in Figure 8.

Header 49 of regenerator 60 is connected with header 48 of regenerator 61 by a main 64. A main 65 connects header 49 of regenerator 62 with header 48 of regenerator 63. The two mains 64, 65 are connected by a main 66.

The top headers 48 of regenerators 60 and 62 are connected by a main 67. The bottom headers 49 of the regenerators 61, 63 are interconnected by a main 68.

In the apparatus of Figure 8 streams of nitrogen rectification product and air flow alternately over the packing units disposed within the regenerator pairs 58, 59, the nitrogen imparting its cold content to the packing members and the air recovering this cold when it flows thereover during the succeeding step of the process. Oxygen rectification product flows through main 67, headers 48, tubes 31 giving up its cold content to the packing members, which cold content is recovered by the air passing over the packing members. The oxygen leaves regenerators 61, 63 through main 68. A portion of the oxygen flowing through mains 64, 65 is withdrawn through line 66 by blower 69 which recirculates the portion thus withdrawn through non-reversing heat exchanges 70 and 71 into the oxygen line 72 leading from the rectification system, which may be of any well-known type, to the main 67 communicating with the headers 48. In line 72 the recirculated oxygen mixes with the stream of oxygen flowing from the rectification system, the resultant oxygen stream flowing through main 67, headers 48, tubes 31 within regenerators 60, 62, mains 64, 65, a portion being withdrawn through main 66 and the remainder passing

through headers 48 in regenerators 61, 63, tubes 31 in regenerators 61, 63 and exiting through main 68. The recirculated oxygen passing through heat exchanger 70 flows in heat exchange relation with a minor portion of the air leaving one or the other of the regenerator pairs 58, 59, this minor portion of the air being thus warmed to a temperature such that when introduced into an expander 73 liquefaction of air within this expander does not take place. From the expander 73 the expanded air may be supplied to the low pressure stage of the rectification system.

In exchanger 71 the recirculated oxygen flows in indirect heat exchange relation with nitrogen which flows from the rectification system through exchanger 71 and thence through line 74 leading to the regenerators. Thus the nitrogen enters the regenerator pairs 58, 59 at a higher temperature than would otherwise be the case. This nitrogen flows through one of the regenerator pairs 58, 59 and removes therefrom carbon dioxide and other condensibles deposited therein during the preceding step of the process. The efficiency of the purging action of the nitrogen is materially improved by its entering the regenerator pairs 58, 59 at such higher temperature as hereinabove described, since the pre-heating of the nitrogen in this manner results in temperature conditions within the regenerator optimum for the removal of carbon dioxide.

Reversal of flow of nitrogen and air through regenerator pairs 58, 59 is accomplished by a pair of reversing valves 75, 76. Reversing valve 75 is provided with an air inlet line 77, a pair of lines 78, 79 leading to ports 56 of the regenerators 61, 63 and a nitrogen exit line 80. The other reversing valve 76 is provided with a pair of lines 81, 82 leading to the ports 55 of regenerators 60, 62, nitrogen line 74 leading from the non-reversing exchangers 71 and an air exit line 83 leading to the rectification system and having a branch 84 through which a minor portion of the air, as hereinabove described, flows through exchanger 70 to the expander 73.

In the operation of the apparatus of Figure 8, air at a pressure of 60 to 100 pounds and a temperature of from 70° to 110° F. is supplied through line 77, and, as indicated by full line valve settings, flows through valve 75, line 79 into and through regenerators 63, 62 where it is cooled to a temperature close to its dew point at the pressure prevailing in this regenerator. The thus cooled air exits through line 82 into valve 76 from which the air flows through line 83, a major portion passing to the rectification system and the remaining minor portion flowing through line 84, heat exchanger 70 to expander 73. From this expander the expanded air at a pressure of 5 to 12 pounds passes to the low pressure stage of the rectification system. Simultaneously nitrogen flows through line 74 into valve 76, line 81 into and through regenerators 60, 61 giving up its cold to the packing units in these regenerators. The thus warmed nitrogen exits through line 78, valve 75 and nitrogen exit line 80.

Oxygen from the rectification system flows through line 12, main 67, headers 48, tubes 31 within the regenerators 60, 62, headers 49, connecting mains 64, 65. A portion of this oxygen is withdrawn as product through main 68 after its flow through headers 48, tubes 31 in regenerators 61, 63. The remainder is recirculated by blower 69 through exchangers 70, 71 into line

72 where the recirculated oxygen augmented by oxygen from the rectification system flows through main 67, headers 48, tubes 31 in regenerator pairs 58, 59, a portion being recirculated as hereinabove described.

Upon reversal, which may take place every three minutes, as indicated by the dotted line valve settings, air flows through valve 75, line 78, regenerators 61, 60 and is refrigerated close to its dew point in its flow through these regenerators. The air exits through line 81 and flows through valve 76 and thence through the same flow path as hereinabove described. Simultaneously nitrogen flows through line 74, valve 76, line 82, regenerators 62, 63, exiting through line 79, valve 75 and nitrogen exit line 80. Oxygen flows through the same paths as during the preceding step of the process, namely, through the tubes 31 in the regenerator pairs 58, 59, cocurrently with the stream of nitrogen flowing through regenerators 62, 63 and countercurrent to the stream of air flowing through regenerators 61, 60 in indirect heat exchange relation therewith. The nitrogen which alternately flows through one or the other of the regenerator pairs 58, 59 removes therefrom carbon dioxide and other condensibles deposited therein from the air during the preceding step of the process.

The regenerator assembly of Figure 9 differs from that of Figure 8 chiefly in that (1) it involves two sets of regenerators, one for the reversal of air and nitrogen and the other for the reversal of air and oxygen instead of the single set of Figure 8; and (2) the supporting tubes in certain of the regenerators are sealed or "pinched off," or are in the form of solid supporting rods since no flow therethrough takes place.

In Figure 9, 86, 87 are the pairs of regenerators forming the set through which the flow of air and nitrogen takes place alternately and 88, 89 are the pairs of regenerators forming the set through which the flow of oxygen and air takes place alternately, the regenerators of the pairs 88, 89 being approximately one-fourth the volumetric capacity of the regenerators of the pairs 86, 87. Regenerator pair 86 comprises regenerators 90, 91 having the ports 56, 55 interconnected for flow from one regenerator to the other. Regenerator pair 87 comprises regenerators 92, 93 having the ports 56, 55 interconnected; regenerator pair 88 comprises regenerators 94, 95 having the ports 56, 55 interconnected; and regenerator pair 89 comprises regenerators 96, 97 having the ports 56, 55 interconnected. Each of the regenerators 90, 92, 94, 96 structurally is substantially the same as the regenerator of Figure 6 and like parts have been indicated by like reference characters. In the case of the regenerators 91, 93, 95 and 97 the tubes 31 on which the individual packing members are stacked, as hereinabove described, are "pinched off" or otherwise sealed, since no flow therethrough takes place. In lieu of hollow tubes solid supporting rods having a diameter equal to that of opening 16 of the packing member may be used.

Reversal of flow of nitrogen and air through regenerator pairs 86, 87 is accomplished by a pair of reversing valves 98, 99. Valve 98 is connected with ports 56 of regenerators 91, 93 through lines 100, 101, respectively, and has a nitrogen exit line 102 and a branch air inlet line 103 leading from a main air line 104. Reversing valve 99 is connected with the ports 55 of regenerators 90, 92 by means of lines 105, 106, respectively, and has a nitrogen inlet line 107 and an

air exit line 108 connected with the air line 109 leading to the rectification system.

Reversal of flow of oxygen and air through the regenerator pairs 88, 89 is accomplished by a pair of reversing valves 110, 111. Reversing valve 110 is connected with the ports 56 of regenerators 95, 97, respectively, by lines 112 and 113, and has an oxygen exit line 114 and a branch air inlet line 115 leading from the main air line 104. Reversing valve 111 is connected to regenerators 94, 96 by a pair of lines 116, 117, respectively, and is provided with an oxygen inlet line 118 and an air exit line 119 communicating with the main air line 109.

Oxygen line 118 has a valve 120 therein and is provided with a branch 121. Valve 120 regulates the amount of oxygen flowing through branch line 121 and line 118. Lines 122, 123, 124 and 125 lead from the branch line 121 to the inlet ports 51 communicating with the headers 48 in each of the regenerators 96, 94, 92 and 90. The outlet ports 53 leading from the headers 49 disposed in each of the regenerators 96, 94, 92 and 90 communicate with lines 126, 127, 128 and 129 which lead into a recirculating main 130 communicating with the oxygen line 118 at a point between valve 120 and reversing valve 111.

Recirculating line 130 may pass through non-reversing heat exchangers corresponding to exchangers 70, 71, as in the modification of Figure 8. Instead of recirculating oxygen through the circulating system consisting of lines 121, 122, 123, 124, 125, ports 51, headers 48, tubes 31, headers 49 and main 130, other rectification products, such as nitrogen, argon, neon, etc., or an extraneous gas may be recirculated through this system, in which case the circulation system is designed so that it is independent of the oxygen air line 118.

In the operation of the apparatus of Figure 9 air at a pressure of 60 to 100 pounds and a temperature of from 70° to 110° F. is supplied from main air line 104 to the branches 103, 115, and flows through valves 98, 110, lines 101, 113, regenerator pairs 87, 89, exiting through lines 106, 117, valves 99, 111 and lines 108, 119, respectively, into the main air line 109 which leads to the rectification system. Simultaneously nitrogen is supplied from the rectification system through line 107, flows through valve 99, line 105, regenerator pair 86 and exits through line 100, valve 98 and nitrogen exit line 102. Oxygen is supplied through line 118 and flows through valve 111, line 116, regenerator pair 88 and exits through line 112, valve 110 through the oxygen exit line 114. The nitrogen and the oxygen give up their cold content to the packing units in the regenerator pairs 86, 88. The air in flowing over the packing units in the regenerator pairs 87 and 89 is cooled to a temperature close to its dew point at the pressure prevailing in these regenerators. Any carbon dioxide or other condensables contained in the air is deposited in the regenerators.

A portion of the oxygen flows through line 121, branches 122, 123, 124, 125, ports 51, headers 48, tubes 31 in each of the regenerator sections 96, 94, 92, 90, this portion exiting through headers 49, ports 53 and main 130 from which the oxygen flows with the oxygen stream flowing through line 118 into the reversing valve 111. The resultant oxygen stream, as hereinabove described, passes over the packing units in regenerator pair 88.

Upon reversal, which may take place every three minutes, as indicated by the dotted line 75

valve settings, air flows through valves 98, 110, lines 100, 112, through the regenerator pairs 86, 88, lines 105, 116, valves 99, 111, lines 108, 119, respectively, to the air line 109. Nitrogen flows through valve 99, line 106, regenerator pair 87, exiting through line 101, valve 98 and thence through the nitrogen exit line 102. A portion of the oxygen from the rectification system is recirculated through the tubes 31 in each of the regenerators 90, 92, 94, 96, as hereinabove described, and mixes with the oxygen stream flowing through line 118 into the reversing valve 111. This mixed oxygen stream flows through line 117, regenerator pair 89, exiting through line 113, valve 110 and oxygen exit line 114. The nitrogen which alternately flows through one of the regenerator pairs 86, 87 and the oxygen which alternately flows through one of the regenerator pairs 88, 89 removes therefrom carbon dioxide and other condensables deposited therein during the preceding step of the process.

It will be noted the regenerator of this invention has an exceptionally high surface area of cold exchanger surface per unit of volume of regenerator. With the design of packing units hereinabove described involving packing members approximately 3 inches square made of aluminum having a thickness of .032 inch and otherwise dimensioned as hereinabove described, the regenerator may have about 365 square feet of cold exchanger surface per cubic foot of regenerator volume. The turbulent flow caused by the grouping of the individual packing members within each unit, as hereinabove described, further improves the cold transfer efficiency of the regenerator. The regenerator is therefore of exceptionally high cold transfer efficiency. This makes it possible to have the volumetric space through which the nitrogen and oxygen on the one hand and air on the other flows relatively small thereby minimizing reversal losses. In the modification of Figure 8 in which no reversal of oxygen flow takes place, such reversal losses are still further minimized.

The construction and design of the packing members permit their ready assembly on the supporting tubes 31. Hence, the regenerator is simple to form and assemble. Moreover, the flow through the channels in the packing units and the tubes 31 is in a general longitudinal direction with consequent minimum pressure drop of fluid flowing through each regenerator.

The regenerators shown in Figures 6, 8 and 9 are in a vertical position and in the case of Figures 8 and 9 the air enters at the lower end and the products of rectification at the upper end. If desired, the air could instead be introduced at the upper end and the products of rectification at the lower end. Preferably the ports and associated headers at the warmer end of the regenerators are larger than the corresponding parts at the cooler end to compensate for volume changes occurring in the gaseous fluids flowing therethrough.

In Figures 1, 2, 4 and 5, the packing members embodying this invention are shown associated with the cylindrical tubes or supporting rods which are generally preferred. However, these packing members may be made for use with hexagonal, square or other shaped tubes or supporting rods; hence, the terms "tube" and "supporting rod" are used in a broad sense and are intended to include all such polygonal tubes and supporting rods.

It will be understood different embodiments of

the invention can be made without departing from the scope of this invention. Thus, while each regenerator pair of Figures 8 and 9 has been shown as consisting of two regenerators, regenerator assemblies may be constructed containing any desired number of regenerators placed in series and/or parallel. Accordingly, it is intended that all matter contained in the above description or shown in the accompanying drawings shall be interpreted as illustrative and not in a limiting sense.

What is claimed is:

1. A regenerator packing member comprising a thin plate-like polygonal member of high heat conducting material, a flanged mounting opening therein, narrow integral flanges on at least two opposite peripheral edges thereof and having in the face thereof a multiplicity of closely spaced passages formed by cutting the plate-like member along closely spaced lines and deflecting substantially all of the material between contiguous lines to provide vanes defining said passages, the said vanes each extending substantially equidistantly above and below the plane of the face of the plate-like member and lying in a plane at an angle to the plane of the face of the plate-like member, said member when assembled with other like members with the flanges of one member disposed in substantially abutting relationship with the face of a contiguous member providing an exceptionally large mass of high heat conducting material per unit of regenerator volume permeated by a multiplicity of said passages for flow of a fluid medium therethrough in surface contact with said high heat conducting material.

2. A regenerator packing member as defined in claim 1, in which the high heat conducting material is aluminum and the thickness of said material does not exceed .040 inch.

3. A regenerator packing member as defined in claim 1, in which the high heat conducting material is copper and the thickness of said material does not exceed .040 inch.

4. A regenerator packing member comprising a plate-like polygonal member of a thickness not exceeding .040 inch of high heat conducting material having a central mounting opening therein, narrow integral flanges on at least two opposite peripheral edges thereof and having in the face thereof two series of closely spaced passages separated by a narrow face portion of said plate-like member, each of said series of said closely spaced passages being formed by cutting the plate-like member along closely spaced lines extending in a substantially straight line direction from said narrow portion to near the periphery of said plate-like member, and deflecting the material between contiguous lines to provide vanes defining said passages, said vanes each extending in a plane at an angle of from 60° to 90° to the plane of the face of the plate-like member and being dimensioned so that they do not extend beyond said flanges, said member when assembled with other like members on a support passing through said central opening with the flanges of one member disposed in substantially abutting relation with the face of a contiguous member providing an exceptionally large mass of high heat conducting material per unit of regenerator volume permeated by a multiplicity of said passages for flow of a fluid medium therethrough in surface contact with said high heat conducting material.

5. A regenerator packing member comprising a substantially square aluminum plate of a thick-

ness not exceeding .040 inch having a central supporting opening therein, integral spacer flanges on said plate, said plate having in the face thereof two series of closely spaced passages formed by cutting the plate along closely spaced lines extending in a generally longitudinal direction from near the medium line of said plate to the peripheral edges containing said flanges, said lines being substantially perpendicular to said peripheral edges, and deflecting the material between contiguous lines to provide vanes defining said passages, said vanes each being disposed in a plane at substantially right angles to the plane of the plate, the two series of closely spaced passages being separated by a portion of the plate extending thereacross in a substantially straight line direction which when extended intersects the said central opening, said plate when placed with other like plates on a support passing through said central opening with the flanges of one plate in substantially abutting relation with the face of a contiguous plate providing an exceptionally large mass of aluminum per unit of exchanger volume permeated by a multiplicity of said passages for flow of a fluid medium therethrough in surface contact with the aluminum.

6. A regenerator packing unit comprising a supporting rod, a plurality of thin polygonal plate-like members of high heat conducting material, each having a central opening of a cross section area substantially equal to that of said supporting rod and mounted thereon with the rod passing through the central openings of the plate-like members, each plate-like member having narrow integral spacer flanges on at least two peripheral edges thereof and having in the face thereof a multiplicity of closely spaced passages formed by cutting the plate-like member along closely spaced lines and deflecting the material between contiguous lines to provide vanes defining said passages, said plate-like members being disposed on said supporting rod with the flanges of each plate-like member except a terminal member in substantially abutting relation with the face of a contiguous plate-like member.

7. A regenerator packing unit as defined in claim 6, in which each plate-like member is of aluminum of a thickness not exceeding .040 inch, and the flanges have a depth such that they provide a clearance of .003 inch to .020 inch between the edges of the vanes of contiguous plate-like members mounted on said supporting rod with the flanges of one plate-like member abutting the face of a contiguous member.

8. A regenerator packing unit as defined in claim 6, in which each plate-like member is of copper of a thickness not exceeding .040 inch, the flanges have a depth such that they provide a clearance of .003 inch to .020 inch between the edges of the vanes of contiguous plate-like members mounted on said supporting rod with the flanges of one plate-like member abutting the face of a contiguous member.

9. A regenerator packing unit comprising a supporting rod, a plurality of thin polygonal plate-like members of high heat conductivity each having a central opening of a cross sectional area substantially equal to that of said supporting rod stacked thereon with the rod passing through said central opening, each plate-like member having integral spacer flanges extending from the plane of said plate-like member on two opposite peripheral edges and having in the face thereof two groups of closely spaced passages formed by cutting the plate-like member along closely

13

spaced lines extending in a general longitudinal direction from near the median line of said plate-like member to but short of the peripheral edges containing said flanges and deflecting the material between contiguous lines to provide vanes defining said passages, said vanes each extending in a plane at substantially right angles to the plane of the plate-like member and being dimensioned so that they do not extend beyond said flanges, said plate-like members being stacked on said supporting rod so that the flanges of each member of the stack, except a terminal member, are in substantially abutting relationship with the face of a contiguous member of the stack and the said stack provides an exceptionally large mass of high heat conducting material per unit of regenerator volume permeated by a multiplicity of said passages for flow of the fluid medium therethrough in surface contact with said high heat conducting material.

10. A regenerator packing unit as defined in claim 9, in which the plate-like members have a thickness not exceeding .040 inch and are of aluminum.

11. A regenerator packing unit as defined in claim 9, in which the plate-like members are substantially square and are arranged in groups on said supporting rod with the plate-like members in each group having the passages therein extending in substantially the same direction and the passages in the plate-like members of alternate groups extending in a direction at substantially right angles to the direction of the passages in the plate-like members of the remaining groups.

12. A regenerator for the recovery of the cold content of the rectification products produced in the rectification of air to produce oxygen, in combination, a housing having at one end an inlet for one of said rectification products and at the other end an exit therefor, a header in said housing at the said first-mentioned end thereof, a plurality of hollow tubes leading from said header, a stack of polygonal plate-like members on each tube with the sides of said plate-like members disposed close to the sides of the plate-like members on the contiguous tubes, each plate-like member having a thickness not exceeding .040 inch, being of high heat conducting material, having narrow integral spacer flanges on at least two peripheral edges thereof and having in the face thereof a multiplicity of closely spaced passages formed by cutting the plate-like member along closely spaced lines and deflecting the material between contiguous lines to provide vanes defining said passages, said vanes being dimensioned so that they do not extend beyond said flanges, said plate-like members being stacked so that the flanges of each member in the stack, except a terminal member, are disposed in substantially abutting relationship with the face of a contiguous member, thereby providing an exceptionally large mass of high heat conducting material per unit of regenerator volume permeated by a multiplicity of said passages for flow of the first-mentioned rectification product therethrough in surface contact with the high heat conducting material, a header in said housing at the said other end thereof with which the said hollow tubes communicate, an air inlet disposed at the said other end of said housing, and an air exit disposed at the said first-mentioned end.

13. A regenerator as defined in claim 12, in which the plate-like members are of aluminum.

14

14. A regenerator for the recovery of the cold content of the rectification products produced in the rectification of air to produce oxygen, comprising, in combination, a longitudinally extending housing having at one end an inlet for one of said rectification products and at the other end an outlet, a header in said housing at the said first-mentioned end thereof, a plurality of hollow tubes leading from said header for flow therethrough, said tubes being substantially equally spaced throughout the cross sectional area of the portion of said housing through which they extend, a second header in said housing into which said tubes extend, a stack of thin polygonal plate-like members of high heat conducting material mounted on each tube with the tube passing through the central openings of the plate-like members of the stack, each plate-like member having a central opening of a cross sectional area substantially equal to that of the overall cross sectional area of the tube passing therethrough, each plate-like member having narrow integral spacer flanges on two opposite peripheral edges thereof and having on the face thereof two series of closely spaced passages separated by a narrow portion of said plate-like member, each of said series of said closely spaced passages being formed by cutting the plate-like member along closely spaced lines extending in a substantially straight line direction from said narrow portion to near the periphery of said plate-like member and deflecting the material between contiguous lines to provide vanes defining said passages, said vanes each extending in a plane at substantially right angles to the plane of the plate-like member and being dimensioned so that their depth does not exceed that of said flanges, each of said stacks of said plate-like members having the flanges of each plate-like member, except a terminal plate-like member, in substantially abutting relationship with the face of a contiguous plate-like member, said tubes with said plate-like members thereon substantially completely occupying the cross sectional extent of said housing and providing an exceptionally large mass of high heat conducting material per unit of cold regenerator volume permeated by a multiplicity of said passages for alternate flow of air and rectification product therethrough in surface contact with said plate-like members of high heat conducting material.

15. A regenerator as defined in claim 14, in which the plate-like members are substantially square, of a thickness not exceeding .040 inch and the plate-like members of each stack are arranged in groups with the plate-like members in each group having the passages therein extending in substantially the same direction and the passages in the plate-like members of alternate groups extending at substantially right angles to the direction of the passages in the remaining groups.

16. A regenerator assembly for use in the recovery of the cold content of the rectification products produced in the liquefaction and rectification of air to produce oxygen, comprising, in combination, two pairs of regenerators, means for passing air through one pair of regenerators while concurrently passing a rectification product through the other pair of regenerators, valve means for effecting reversal of flow so that air flows through the regenerator pair through which the rectification product had previously passed and the rectification product flows through the regenerator pair through which the air had pre-

15

viously passed, each pair of regenerators comprising a colder and warmer regenerator, headers disposed at the opposite ends of each colder regenerator, tubes connecting the headers and disposed within each of said colder regenerators, regenerator packing within each regenerator, and means for passing a fluid through said headers and the connecting tubes within each of said colder regenerators.

17. A regenerator assembly for use in the recovery of the cold content of the rectification products produced in the liquefaction and rectification of air to produce oxygen, comprising, in combination, a set of regenerators comprising two pairs of regenerators, one pair for the flow of nitrogen rectification product therethrough while air flows through the other pair and upon reversal air flows through the pair through which had previously passed the nitrogen and the nitrogen through the pair through which had previously passed the air, a second set of regenerators comprising two pairs of regenerators, one pair for the flow of oxygen rectification product while air flows through the other pair and upon reversal air flows through the pair through which had previously passed the oxygen and the oxygen
